(57) **CLAIM**

The ornamental design for server, as shown and described.

DESCRIPTION

FIG. 1 is a front perspective view of a server, showing a first embodiment of my new design;

FIG. 2 is a rear perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view thereof;

FIG. 9 is a another front perspective view thereof, showing the server in an exploded state;

FIG. 10 is a front perspective view of a server, showing a second embodiment of my new design;

FIG. 11 is a rear perspective view thereof;

FIG. 12 is a front view thereof;

FIG. 13 is a rear view thereof;

FIG. 14 is a top view thereof;

FIG. 15 is a bottom view thereof;

FIG. 16 is a left side view thereof;

FIG. 17 is a right side view thereof;

FIG. 18 is a another front perspective view thereof, showing the server in an exploded state;

FIG. 19 is a front perspective view of a server, showing a third embodiment of my new design;

FIG. 20 is a rear perspective view thereof;

FIG. 21 is a front view thereof;

FIG. 22 is a rear view thereof;

FIG. 23 is a top view thereof;

FIG. 24 is a bottom view thereof;

FIG. 25 is a left side view thereof;

FIG. 26 is a right side view thereof; and,

(Continued)

FIG. 27 is another front perspective view thereof, showing the server in an exploded state.

The dot-dash-dash broken lines in the exploded views of FIGS. 9, 18 and 27 indicate the order of assembly and form no part of the claimed design.

The evenly-dashed broken lines illustrate portions of the server that form no part of the claimed design.

1 Claim, 27 Drawing Sheets
